(57) CLAIM

I claim the ornamental design for a top for a midsize UTV, as shown and described.

DESCRIPTION

FIG. 1 is a side view of a top for mid size UTV showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

In the drawings, the broken lines depict a UTV that forms no part of the claimed design.
